UNITED STATES PATENT OFFICE.

HERMAN J. MÜLLER, OF PHILADELPHIA, PENNSYLVANIA, ASSIGNOR TO THE HENSEL SILK MANUFACTURING COMPANY, OF PHILADELPHIA, PENNSYLVANIA, A CORPORATION OF PENNSYLVANIA.

DESIGN FOR FRINGE.

42,857.

Specification for Design.

Patented Aug. 6, 1912.

Application filed February 13, 1912. Serial No. 677,368. Term of patent 14 years.

To all whom it may concern:

Be it known that I, HERMAN J. MÜLLER, a citizen of the United States, and a resident of Philadelphia, Pennsylvania, have invented a certain new, original, and ornamental Design for Fringe, of which the following is a specification, reference being had to the accompanying drawing, forming a part thereof.

The drawing is a face view of a portion of the fringe showing my design.

I claim:

The ornamental design for a fringe, as shown.

HERMAN J. MÜLLER.

Witnesses:

AUGUSTUS B. COPPES,
Wm. A. BARR.
